US00D979782S

(12) **United States Design Patent** (10) Patent No.: **US D979,782 S**
(45) Date of Patent: **** Feb. 28, 2023**

(54) **COSMETIC SKIN CARE DEVICE**

(71) Applicant: **Artistic & Co., Ltd.**, Aichi (JP)

(72) Inventors: **Minjae Sung**, Hwaseong-si (KR); **Jin Park**, Suwon-si (KR); **Jeongseon Park**, Yongin-si (KR); **Man Jin Oh**, Suwon-si (KR); **Dong Shin Jo**, Hwaseong-si (KR)

(73) Assignee: **ARTISTIC & CO., GLOBAL CO., LTD**, Gifu (JP)

(**) Term: **15 Years**

(21) Appl. No.: **29/790,815**

(22) Filed: **Dec. 16, 2021**

Related U.S. Application Data

(62) Division of application No. 35/510,468, filed on Mar. 30, 2020 (U.S. filing date under 35 U.S.C. 384), and having an international filing date of Mar. 30, 2020, now Pat. No. Des. 959,687.
